UNITED STATES PATENT OFFICE.

ERNST G. K. ANDERSON, OF CHICAGO, ILLINOIS, ASSIGNEE, BY MESNE ASSIGNMENTS,
TO APPLETON ELECTRIC CO., OF CHICAGO, ILLINOIS, A CORPORATION OF ILLINOIS.

SWITCH CONTROL FOR SPOTLAMPS.

Application filed May 31, 1921. Serial No. 472,648.

This invention relates to improvements in switch controls for signal or spot lamps of that type designed for use on automobiles, and which are adapted to be supported by universal mountings designed to adapt the rays of the lamp to be thrown in substantially all directions. The invention refers more particularly to a novel automatic control mechanism for the lamp switch which is so located relatively to the switch actuating member and to the relatively movable parts of the mounting as to open the switch in the lamp circuit in a predetermined position or positions of movement of the lamp mounting, and thereby extinguish the lamp.

It has been a common fault in the use of universally mounted spot lamps of this character that the lamp can be so manipulated and, in some instances, intentionally and maliciously, as to throw the full glare of the light into the eyes of an oncoming driver or into the eyes of pedestrians, which often results in temporarily blinding the driver and causing him to lose the roadway and the control of his car, and causes confusion with pedestrians, with frequent results of serious accidents. It is most desirable in a lamp of this character that the construction of the lamp mounting may be such as to permit a wide or substantially universal range of forward throw of the light shaft, both laterally and horizontally, and it is the object of the present invention to provide in a lamp mounting of this character means which will permit freedom of manipulation of the lamp while, at the same time, avoiding throwing the full glare of the light rays straight forward into the eyes of an oncoming driver or of pedestrian.

To attain this desirable result it is the further object of the invention that the lamp switch can be so controlled as to open the lamp circuit when the lamp is directed straight ahead, whether the lamp is being moved horizontally or vertically through this position, and thus compel the driver of the car who is operating a lamp thus equipped to shift the adjustment to one side or, or above or below a straight ahead position, in order to regain control of the light of his spot or signal lamp.

A further object of the invention is to provide a control device of this character, a portion or portions of which can be adapted

to lamp mountings of different structures, such, for instance, as where the supporting brackets, which constitute means of support of the lamp mounting on the vehicle, are located at different elevations with respect to the parts of the lamp mountings which carry the switches.

Another object of the invention is to provide means for adjusting the parts of the mounting so as to adapt the same to the switch control member to compensate for inaccuracies in the mounting structure, itself or to differently located parts on the car which supports the lamp.

Further objects are to simplify and improve switch controls for universally adjustable spot lamp mountings, and the invention consists in the combination and arrangement of the parts shown in the drawings and described in the specifications, and is pointed out in the appended claims.

In the drawings:

Figure 1 is a plan view of a spot lamp and universal mounting therefor equipped with my improved switch control mechanism.

Figure 2 is a rear view thereof.

Figure 3 is an enlarged detail plan view, with parts broken away, showing the operative elements of the control in one position of adjustment.

Figure 4 is an enlarged rear view thereof, showing the parts in another position of adjustment with parts in section.

Figure 5 is a cross section on line 5—5 of Figure 3.

Figure 6 is a perspective view of one of the elements of the control mechanism.

Figures 7 and 8 are plan and rear views, respectively, of another type of universal lamp equipped with my improved switch control mechanism.

As shown in Figures 1 to 5 of the drawings, my improvements are shown as applied to a type of lamp and mounting which embodies in its construction a rewinding reel structure for taking up the lamp cord, whereby the cord can be unwound from the reel when the lamp is detached from its support so that the lamp can be used as a trouble lamp, the cord being automatically rewound on the reel when the lamp is again replaced at its normal station on the vehicle. Such a construction is shown in my prior United States Letters Patent, Num-

ber 1,309,678, granted July 15, 1919. In such construction the rewinding reel is enclosed in a casing 10.

11 designates the casing of the spot lamp which carries the usual lamp bulb (not shown). 12 designates the front lens, and 14 designates a stem which extends rearwardly from the casing 11 coaxial with the focal axis of the lamp. The said stem 14 is 10 made hollow, as indicated in Figures 3 and 4, to receive the lamp control switch, designated as a whole in said figures by 15. The type of switch herein indicated is like that shown in my companion application for 15 United States Letters Patent filed on the 25th day of June, 1921, Serial Number 480,-347. It will be understood, however, that the switch control constituting the present invention is capable of use with other types 20 of switches and with other types of universal lamp mountings, one other type of mounting being illustrated in Figures 7 and 8, hereinafter to be described.

The universal mounting shown in Figures 25 1 to 5, inclusive, embraces as an element thereof an elbow fitting or carrier member 16, one arm 17 of which is rotatively connected to a hollow stud or carrier rod 18 which can be formed integral with the stem 30 14. Said joint or connection can be like that illustrated in my companion application for United States Letters Patent filed on 9th day of June, 1921, Serial Number 476,227, and need not be further herein described, 35 except to say that the rotational connection between the carrier arm or member 16 17 and the stud or carrier rod, afforded by an extension of said rod fitted in a socket in the carrier member 18 enables the lamp casing 40 to be swung in a vertical plane about the axis of said joint thus produced. The other arm 20 of said elbow fitting or carrier member 16 terminates in a downwardly extending cone-like bearing 21 which fits within 45 a tapered bearing in a member 22 that is formed on a ring 23 by which the reel casing 10 is carried. A nut 24 threaded on the member 22 forces the joint tapers into frictional contact to permit the elbow fitting 50 to be turned with a moderate manual force, while normally holding the rotative joint at this point fixed in adjusted positions. The latter joint permits the lamp structure to be swung in a horizontal plane.

55 Referring now to the details of the switch control mechanism whereby the lamp circuit switch is opened in predetermined positions of adjustment of the universal mounting, said parts are made as follows:

60 It may be preliminarily stated that the switch mechanism 15 within the stem 14 is directly controlled by a switch actuator 25, which is disposed parallel to the axis of the horizontal arm of the fitting 16 and is provided with a finger piece or arm 29 by which

the switch may be manually controlled. The actuator 25 is mounted for rocking and axial movement in lugs 26, shown as formed integral with the stud 18. It has at its inner end a wedge formation 27 and also an 70 oblong rectangular formation 28, as is more clearly shown in my aforesaid companion application Serial Number 480,347, whereby the blades of the switch are adapted to be separated, and the switch thereby opened, 75 either through axial movement of the actuator or through rotational movement thereof. The rotational movement of said actuator member is manually controlled by said arm 29. The axial movement thereof is automatically controlled by the control mechanism now to be described.

30 designates a control element which is of general U shape. It comprises specifically two parallel arms 31, 31 having free rounded contact ends 32, 32. Its closed portion 33 terminates in a rounded nose 34, whose radius is considerably shorter than the general radius of the closed portion. For the purpose of adapting the said U-shaped control element to lamp mountings of different types, the said U-shaped portion is offset from the parallel arms 31 thereof, as will hereinafter be more fully described.

The said control element 30 is supported on the elbow fitting 16, in the construction shown in Figures 1 to 5, inclusive. Its support consists of a saddle member, designated as a whole by 35, which is rounded to fit closely on the rounded horizontal arm of said fitting. It abuts at its forward edge against the tightening nut 35' of the joint between the said horizontal arm and the lamp stem stud 18. Said saddle member is fixed to the fitting by screws 36, 36 which extend through slots 37 in the saddle plate and are threaded to the wall of the horizontal arm of the elbow fitting. Said slots 105 permit slight angular adjustment of the saddle plate on said fitting for a purpose which will hereinafter more fully appear.

The saddle plate is provided at its opposite edges and at the sides of the horizontal arm 17 of said fitting with guide sleeves 38 in which fit and are adapted for slight axial movement the straight arms 31 of the U-shaped control element 30. The rounded end 32 of said arms project somewhat beyond the forward ends of said guide sleeves 38 and are adapted in certain positions of adjustment of the lamp mounting for engagement with the correspondingly rounded ends 25' of the switch actuator 25. The axial displacement of said arms 31 of the control element 30 in said guide sleeves is limited by a lug 40 in one of the guide sleeves 38 which projects into an inwardly facing recess 41 on the inner side of the adjacent arm of the control element 30. This detail can be pro-

duced in the construction shown by making the guide sleeves 38 slightly less than a full cylindrical cross section and by pressing the edge of the free margin of the sleeve inwardly to form said lug 40. It may be here observed that one lug 40 and its corresponding notch 41 at one side of the control mechanism is sufficient for each installation. The control element 30, however, is adapted to be reversed for installation in the type of mounting shown in Figures 7 and 8, as hereinafter described, so that it becomes desirable to provide both the straight arms of the U-shaped control element with a notch 41.

15. The nose 34 at the closed portion of the U-shaped control element is adapted for contact with a fixed part which may be carried by the bracket 43 which forms means of attachment of the mounting to a fixed part of the vehicle such, for instance, as a windshield frame post. Preferably, however, contact between the nose or closed part of the U-shaped control element is effected between said nose and an adjustable part on said bracket. In practice, this adjustment of the normally fixed element can be both horizontal and vertical.

The form of contact element herein shown comprises the round head 45 of a screw 46 which is threaded into a post 47 that is fixed in the bracket 43 in any suitable manner. Said screw can be locked in a place by a lock nut, as shown. The means for fixing said post in place, to permit vertical adjustment thereof, may constitute a headless set screw 48 that is threaded through the bracket to impinge at its inner end against the lower end of the post. The horizontal adjustment of the screw 46 is effected by slackening the lock nut thereon and adjusting the said screw, by reason of its threaded connection with the post, and afterwards tightening the lock nut.

45. The operation of the switch control mechanism described is as follows:

Figures 1 and 2 show the adjustment of the mounting in position to direct the light shaft of the lamp straight ahead. In this adjustment it will be noted that the nose of the U-shaped control element is in contact with the head of the screw 46, and it will also be noted that the rounded end 32 of one of the straight arms 31 of the control member 30 is aligned, and in contact, with the rounded end of the switch actuator pin 25 of the switch. Therefore, the control member 30 is in position to thrust said actuator pin forwardly and thereby actuate the switch elements so as to open the switch and extinguish the electric lamp. The position shown in Figures 1 and 2 is the adjustment which is objectionable in the use of the spot lamp, inasmuch as this is the adjustment in which the light shaft from the lamp is thrown directly ahead and is most likely to be pro-

jected into the eyes of an oncoming driver or pedestrians on the roadway ahead.

Figure 3 shows a horizontal adjustment of the lamp mounting at an angle to its straight ahead position so as to shift the nose of the U-shaped control element out of operative contact with the head 45 of the screw 46. When the said control element is thus adjusted away from the contact screw head 45, it is caused to shift rearwardly a distance due to the limiting action of the lug 40 and notch 41. Such shifting may be effected either by applying a restoring spring directly to the control element, or by employing the resiliency of the U-shaped spring in the switch mechanism itself, as clearly shown and described in connection with the switch mechanism illustrated in my aforesaid companion application, Serial Number 480,347. The latter restoring function is simple and is preferred inasmuch as a single spring can be made to restore the actuator pin and the switch control element. In the adjustment shown in Figure 3, therefore, and with the light shaft directed horizontally to one side of the straight line position of the lamp, the lamp may be swung further horizontally towards the same direction shown in Figure 3, or swung vertically without actuating the lamp switch, and, therefore, utilize the full power of the lamp. If, however, the lamp casing be swung to the other side of its straight ahead position, the switch will be opened and the light extinguished as the nose 34 passes the screw head 46.

In the adjustment of the parts shown in Figure 4, the elbow fitting 16 is assumed to be in the same position as shown in Figure 1, with the nose 34 of the control element 30 in contact with the rounded head of the screw 46. In the position of adjustment shown in said Figure 4, however, the lamp casing has been swung downwardly from its normal straight ahead position so as to direct the light shaft on the roadway near the car which carries the lamp. In this position of the parts it will be noted that the actuator pin 25 has been raised above the end 32 of the arm 31 of the control element so that said pin is, by its own restoring spring, in its rearmost position, or in a position in which the lamp switch is closed. The lamp casing can be swung further downwardly from the position shown in Figure 4 without interfering with the light. If, however, the lamp casing be swung upwardly past its straight ahead position, the switch will be momentarily opened when the parts are in the straight ahead position of the lamp, the rounded ends of the actuator pin and arm 31 serving to push the actuator pin inwardly.

From what has been said it will be understood that the control mechanism described permits the lamp to be adjusted uni-

versally and its light shaft to be projected in all directions within the range of its movement and, after the switch has been once closed by hand, it will remain closed except for the short arc of movement of the lamp, either in its horizontal or vertical sweep, at a time when occupying or passing through the straight ahead adjustment of the lamp. It is obvious that a driver carelessly or maliciously manipulating the spot lamp cannot project the light straight ahead into the eyes of an oncoming driver or pedestrians ahead of the vehicle, and that when the adjustment is favorable for such 10 objectional projection of the light shaft, the control of the light will be automatically taken away from the driver.

In Figures 7 and 8 my improvements are shown as adapted to a type of spot lamp 20 which embraces a simple universal mounting without the rewinding reel shown in Figures 1 and 2. One of the features of my invention is embraced in the offset construction of the control member 30 whereby 25 it can be used equally well in both types of lamps. In Figures 1, 2, 3, and 4 it will be noted that the U-shaped portion of the control element is offset downwardly from the arms 31 and their guide and supporting sleeves. In Figures 7 and 8 the same element is disposed with its U-shaped portion offset upwardly for contact with a fixed abutment on the fixed part of the mounting.

The universal mounting shown in Figures 35 7 and 8 is relatively simple, it being like that shown in my companion application for United States Letters Patent filed on 27th day of June, 1921, Serial Number 480,561. It embraces a rigid bracket member 50 that 40 is attached to a fixed support 51, as the post of a windshield frame, a horizontally swingable member 52 that is joined to the fixed part 50 by a rotative joint 53, the axes of which is in a vertical plane, and a second rotative joint 54 between said member 52 and the fixed lug 55 of the stem 14 that extends rearwardly from the lamp casing 11. In 45 the construction shown in said Figures 7 and 8, the saddle member 56, in the sleeves 50 57 of which the arms 31 of the control member 30 are slideable, can be made narrower than the saddle member 25 shown in the other figures, and is adjustably attached to the mounting member 52 by a screw 58, 55 which extends through a transverse slot 59 of the saddle member and is threaded into the mounting member 52. The contact between the forward rounded ends 32 of the control member 30 and the switch actuator 60 pin 25 is the same as shown in the figures before described. The contact of the rear end or nose 34 of said control member, however, is with a pin 60 that extends upwardly from the fixed member 50 of the mounting.

65 In the construction shown in Figures 7

and 8 it will be noted that inasmuch as the contact pin 60 is above the center of the rotative joint between the members 52 and 55, and inasmuch as the guide sleeves 57 of the saddle 56 lie substantially in the plane of the 70 axis of the stem 14 of the lamp casing, the offset closed end of the control element 30 is raised above the guide arms thereof, instead of being below said guide arms of the 75 previously described figures. It will be obvious, however, that the functions of the several elements and the operation thereof is identical with the construction shown in the previously described figures.

I claim as my invention:

1. Switch control for universal spot lamps comprising, the combination with mounting members rotative on axes at right angles to each other, one adapted to support the lamp structure and the other having means of attachment to a fixed support, and an actuator for a controlling switch for the lamp, of a control member slidably mounted on one of said mounting members and adapted for contact with said actuator, and means operative through one sweep of the lamp movement to move said control element in position to engage and axially shift said actuator, and operative in the other sweep of the lamp movement to cause the control member to wipe against said actuator to axially shift said actuator.

2. The combination with the two members of a universal mounting for an electric spot lamp, one having means of attachment to a fixed support and the other adapted to support a lamp casing, and an actuator for a controlling switch of the lamp, of a switch control element slidably mounted on one of said members toward and from said actuator and adapted to be moved endwise by contact with a fixed part of the mounting, towards and in contact with said actuator when one of said mounting members is swung on its axis, and said control element being located in position for side wiping contact with said actuator when the other of said mounting members is swung on its axis.

3. Switch control for universal electric spot lamps comprising, the combination with a universal mounting embracing members which rotate on axes at right angles to each other, with means of attaching one member to a fixed support, a lamp casing attached to the other mounting member, and a lamp controlling switch having an actuator, of a switch control element mounted and slideable on one of said mounting members, a fixed part adapted to engage said control element to shift it into contact with said actuator to control said switch, and means to adjust said fixed part relatively to said control element.

4. Switch control for universal electric spot lamps comprising, the combination with the members of a universal mounting, with

- means of attaching one member to a fixed support, a lamp casing attached to the other mounting member, and a lamp controlling switch having an actuator, of a switch control element mounted and movable on one of said mounting members and adapted, through swinging movement of the mounting member carrying the same, to be shifted endwise for contact with said actuator, and 5 means to limit sliding movement of said control element.
5. Switch control for universal electric spot lamps comprising, the combination with the members of a universal mounting, with 15 means of attaching one member to a fixed support, a lamp casing attached to the other mounting member, and a lamp controlling switch having an actuator, of a switch control element mounted and movable on one 20 of said mounting members, a vertically adjustable stud mounted in a part fixed relatively to said mounting member, and a part carried thereby adapted to contact with said control element in one part of the swinging movement of the latter to shift said control element into contact with said switch actuator.
6. Switch control for universal electric spot lamps comprising, the combination with 30 the members of a universal mounting, with means of attaching one member to a fixed support, a lamp casing attached to the other mounting member, and a lamp controlling switch having an actuator, of a switch control element mounted and slidable on one of said mounting members, said control element being slidable toward and adapted for contact with said actuator, a member mounted in a part fixed relatively to said mounting members and in rear of said control element, and a contact member adjustable in said fixed part toward and from said control element and adapted for wiping contact with the control element.
- 45 7. Switch control for electric spot lamps comprising a lamp casing provided with a rearwardly directed hollow stem formed with a lateral stud, a lamp controlling switch in said stem having an axially movable actuator, and a universal mounting embracing two members, on one of which said stud has rotational adjustment, the other member having means of attachment to a fixed support and having rotational adjustment on an axis at right angles to that of said stud, of a switch control element movably mounted on the latter member and adapted for endwise contact and for side wiping contact at one end with said switch actuator, and said control element being adapted for wiping contact at its other end with a fixed part on the mounting.
8. Switch control for electric spot lamps comprising, in combination with universally 65 mounted members, one having means of attachment to a fixed support and the other adapted to support a lamp casing, and a controlling switch for the lamp provided with an actuator, of a saddle supported on one of the mounting members and provided with a guide, a switch control element supported and axially movable in said guide for endwise contact with said actuator, a part fixed relatively to the mounting adapted for wiping contact with said control element upon operative movement of the member carrying the same, said contact end of the control member and the end of the switch actuator being rounded for wiping contact upon operative movement of the other 70 mounting member.
9. Switch control for electric spot lamps comprising, in combination with universally mounted members, one having means of attachment to a fixed support and the other 85 adapted to support a lamp casing, and a controlling switch for the lamp provided with an actuator, of a saddle supported on one of the mounting members and provided with a guide, a switch control element supported and axially movable in said guide for endwise contact with said actuator, a part fixed relatively to the mounting adapted for wiping contact with said control element upon operative movement of the member carrying the same, said contact end of the control member and the end of the switch actuator being rounded for wiping contact upon operative movement of the other 80 mounting member.
10. Switch control for universal spot lamps comprising, the combination with the members of a universal mounting for the lamp, and a switch actuator for the lamp switch, of a U-shaped control element slidably supported on one of said mounting members with its arms lying on opposite sides thereof, one of said arms being adapted for endwise and wiping contact with said actuator, and a part fixed relatively to said mounting member adapted for wiping engagement with the closed part of said element at one position of one sweep of the 90 lamp, the closed part of said control element being offset from its said arms.
11. Switch control for universal spot lamps comprising, the combination with the members of a universal mounting for the lamp, and a switch actuator for the lamp switch, of a U-shaped control element slidably supported on one of said mounting members with its arms lying on opposite sides thereof, one of said arms being adapted for endwise and wiping contact with said actuator, and a part fixed relatively to said mounting member adapted for wiping engagement with the closed part of said element at one position of one sweep of the 110 lamp, the closed part of said control element being offset from its said arms.
12. Switch control for universal spot lamps comprising, the combination with the members of a universal mounting for the lamp, and a switch actuator for the lamp switch, of a U-shaped control element slidably supported on one of said mounting members with its arms lying on opposite sides thereof, one of said arms being adapted for endwise and wiping contact with said actuator, and a part fixed relatively to said mounting member adapted for wiping engagement with the closed part of said element at one position of one sweep of the 120 lamp, the closed part of said control element being offset from its said arms.
13. Switch control for universal spot lamps comprising, the combination with the members of a universal mounting for the lamp, and a switch actuator for the lamp switch, of a U-shaped control element slidably supported on one of said mounting members with its arms lying on opposite sides thereof, one of said arms being adapted for endwise and wiping contact with said actuator, and a part fixed relatively to said mounting member adapted for wiping engagement with the closed part of said element at one position of one sweep of the 130 lamp, the closed part of said control element being offset from its said arms.

- lamp, the closed part of said control element being offset from its said arms, and means for limiting endwise movement of said control element.
- 5 12. The combination with two members of a universal mounting, one of the members having means of attachment to a fixed support and the other member being adapted to support a lamp structure, and a switch for
- 10 controlling the lamp circuit and having an actuator, of a U-shaped control element, the arms of which are slidably supported on one of the mounting members and provided with contact ends, one of which is adapted
- 15 for axial and wiping contact with the switch actuator, and a part on said fixed support adapted, in one sweep of the lamp, to wipe against the closed end of said U-shaped element to force the control member against
- 20 and actuate the switch actuator.
13. The combination with two members of a universal mounting, one of the members having means of attachment to a fixed support and the other member being adapted
- 25 to support a lamp structure, and a switch for controlling the lamp circuit and having an actuator, of a U-shaped control element, the arms of which are slidably supported on one of the mounting members and provided
- 30 with contact ends, one of which is adapted for axial and wiping contact with the switch actuator, and a part on said fixed support adapted, in one sweep of the lamp, to wipe against the closed end of said U-shaped element to force the control member against
- 35 and actuate the switch actuator, the closed part of the control element being offset relatively to its said arms.
14. An automatic switch control for universal spot lamps comprising the combination with the members of a universal mounting for a lamp and an axially movable switch actuator for the lamp circuit switch, of a control element slidably supported and guided on one of the said mounting members
- 40 towards and from said actuator and adapted to be axially moved by wiping engagement at one end thereof with a fixed part of the structure, said latter end being offset from the plane of the guided portion of said control element, the said switch actuator being carried by a part which swings relatively to the plane of axial movement of the said control element.

In witness whereof I claim the foregoing as my invention, I hereunto append my signature this 27 day of May, 1921.

ERNST G. K. ANDERSON.
